H. J. BECKWITH.

Feather Renovator.

No. 77,571.

Patented May 5, 1868.

UNITED STATES PATENT OFFICE.

HENRY JAMES BECKWITH, OF CHICOPEE, MASSACHUSETTS.

IMPROVEMENT IN MACHINES FOR CLEANING FEATHERS.

Specification forming part of Letters Patent No. 77,571, dated May 5, 1868.

To all whom it may concern:

Be it known that I, HENRY JAMES BECKWITH, of Chicopee, in the county of Hampden and State of Massachusetts, have invented a new combination of parts forming a useful and improved machine for cleaning feathers by the use of steam in connection with said machines; and I do hereby declare that the following is a full and exact description of my invention.

In Figure 1, A B C D represent a sectional view of a wooden box of any convenient form or size. It should be large enough to hold the contents of a large feather-bed. This box has a movable cover to an opening used to admit the feathers. In the center of this box I place a metal cylinder, E E, about ten inches in diameter. It extends from end to end of the box A B C D, and is water and steam tight—that is to say, there is no communication between its interiors and that of the box A B C D. This cylinder is used as a “heater,” to dry the feathers after they have been steamed. Around this heater I place a winding pipe, commencing at P. The windings of the pipe are represented by the letters P S S S S. Its object is to convey steam in the best and simplest manner to the feathers. Openings are made at intervals along the whole pipe. The direction of the steam entering the feather-box from the steam-box is indicated by the arrows on the steam-pipe P S S S S. The head-pieces H I I and L M N are made of cast-iron, and are fitted onto projecting circular flanges on each end of the box, and are represented by the red lines t t. Each of these head-pieces terminates in the form of a tube, as seen at H and M, and form the axis of the machine. The head-piece H I I is also used as a steam-chamber, and supplies, as may be required, the heater E E or the steam-pipe P S S S S. I regulate the entrance of the steam to the heater and steam-pipe by the use of the slide-valve r, which is situated within the steam-chamber H I I. The steam enters into the pipe V, which may be composed of rubber, &c. The steam, having entered the pipe V from the steam-boiler, continues through the hollow axis M into the steam-chamber described.

Fig. 2 represents an end view of the machine without the head-pieces H I I, which shows the form of the slide-valve and its mode of action. It is secured by grooves on each side, into which it moves. The blue circular

disk a represents the open end of the pipe P S S S S, while the opening which leads to the heater is closed by the valves, as represented at d.

Fig. 3 represents a detached view of the same arrangement; but in this case the end view of the steam-pipe P S S S S is represented as shut off by the downward motion of the valve r, leaving thereby the opening to the heater free to receive a charge of steam, while the opening of the steam-pipe P S S S S is cut off. I use the chamber or head-piece L M N as a receiver for the waste steam from the steam-pipe P S S S S through the connecting branches X X. The steam from the heater also enters into the chamber L M N. O is a waste-pipe to allow the condensed steam to escape through the axis M.

Fig. 4 is an end view of the machine at B C. The opening represented by the darts are the terminals of the branch pipes X X described, and the opening E E represents the end of the heater which terminates into the head-piece L M N. T T represent a frame-work for the support of the machine. On the feathers being placed into the steam-box the valve r, Fig. 1, is made to shut the heater and allow the steam to enter the steam-pipe P S S S S. The steam box is shut tightly up, while the machine and contents are made to revolve on the frame-work, causing the steam and feathers to combine. When the feathers are cleaned, the steam is cut off from the steam-pipe. I then remove the cover from the steam-box A B C D, to allow the free steam to escape. At the same time I allow the steam to be admitted into the heater to dry the feathers. When they are dry I turn them out of the box to cool.

What I claim, and desire to secure by Letters Patent of the United States, is—

1. The new combination of the head-piece H I I, secured on the flange t t, in connection with the box A B C D and the slide-valve r, and the steam-pipe P S S S S, arranged to operate together substantially as described.

2. The use of the head-piece L M N, combined with the branch tubes X X and the heater E E, and the waste-pipe O, arranged to operate together substantially as described.

HENRY JAMES BECKWITH.
